Primary Examiner — Leanne Was-Englehart

(57) **CLAIM**

The ornamental design for a clip cable holder, substantially as shown and described.

DESCRIPTION

FIG. 1 shows a perspective view of the clip cable holder in accordance with the present disclosure.

FIG. 2 shows a side view of the clip cable holder in accordance with the present disclosure.

FIG. 3 shows the other side view of the clip cable holder in accordance with the present disclosure.

FIG. 4 shows a front view of the clip cable holder in accordance with the present disclosure.

FIG. 5 shows a rear view of the clip cable holder in accordance with the present disclosure.

FIG. 6 shows a top view of the clip cable holder in accordance with the present disclosure; and,

FIG. 7 shows a bottom plan view of the clip cable holder in accordance with the present disclosure.

The broken lines in the drawings depict environment that forms no part of the claimed design.
